(57) **ABSTRACT**

A multi-frequency antenna comprises a substrate disposed on a clearance area of a circuit board, and a first resonance unit and a second resonance unit located on the surface of the substrate or within the substrate. The first resonance unit is connected to a signal feeding terminal of the circuit board and connected to the second resonance unit via a first filtering element. The first resonance unit forms the first resonance frequency of the multi-frequency antenna, and the first resonance unit, the first filtering element, and the second resonance unit all together form the second resonant frequency. The first filtering element shows a high impedance towards the signal with the first resonant frequency and a low impedance towards the signal with the second resonant frequency. Thus, an antenna with multiple resonant frequencies can be obtained. The material and manufacturing costs of the multi-frequency antenna can thereby be reduced.

MULTI-FREQUENCY ANTENNA**REFERENCE TO RELATED APPLICATIONS**

This non-provisional application claims priority under 35 U.S.C. § 119(a) on Taiwan Patent Application No. 105214817 filed Sep. 29, 2016, the entire contents of which are incorporated herein by reference.

FIELD OF THE INVENTION

The invention relates to a multi-frequency antenna for transmitting or receiving signals with different frequencies, and its advantage is to reduce the size and production costs of multi-frequency antennae.

BACKGROUND

Noting the continued fast progression of wireless communication technologies, wireless communication products are increasingly widely used in our daily lives. The antenna is one of the most important devices for wireless communication products. In general, the antenna may occupy considerable space in wireless communication products. Thus, the reduction of antenna size in order to minimize the size of communication products is a large issue and of great concern.

A microstrip antenna usually refers to an antenna fabricated through the use of microstrip techniques. Microstrip antennae have attracted a great deal of attention due to their plane structure, low cost, ease to be mass produced, and integrated with active components or circuit boards. Thus, microstrip antennae have been widely used in many portable devices that require wireless communication capability, such as mobile phones, smart phones, tablet computers, notebook computers, GPS (Global Positioning System) units, and RFID devices. Despite the many advantages of microstrip antennae, they have several basic disadvantages, such as narrow bandwidth, low gain, and relatively large size.

With the aim of reducing the size and weight of portable computers, the PIFA (Planar Inverted F Antenna) or monopole antenna can be set up on the circuit board of the portable device. However, because of rapid developments in the wireless communication industry, most mobile devices are installed with communication modules that must transmit or receive signals at various frequency bands. Therefore, antennae with multiple resonance frequencies are essential elements in most mobile devices. To design a monopole or PIFA antenna with multiple resonance frequencies, the area or space of a circuit board needs to be large. In actual application, in order to meet the requirement of at least a quarter of the wavelength, the dimensions of the monopole or PIFA antenna cannot be further reduced.

SUMMARY

Therefore, the main objective of the present invention is to provide a multi-frequency antenna that comprises one or more filtering elements connected between two resonance units of the antenna, thereby allowing the antenna to generate two or more resonant frequencies. In one embodiment, the resonance unit may be a resonant segment and the antenna may be a chip antenna.

In order to achieve the above objects, the present invention provides a multi-frequency antenna that comprises a circuit board, at least one substrate, a first resonance unit, a first filtering element, and a second resonance unit. The

circuit board includes a clearance area and at least one signal feeding terminal, and the substrate is disposed within the clearance area. The first resonance unit is connected to the signal feeding terminal, with part or all of the first resonance unit located on the surface of the substrate or within the substrate. The first filtering element is located between the first resonance unit and the second resonance unit, with part or all of the second resonance unit disposed on the surface of or within the substrate. The first resonance unit forms the first resonant frequency of the multi-frequency antenna. The first resonance unit, the first filtering element, and the second resonance unit jointly form the second resonant frequency of the multi-frequency antenna, wherein the second resonant frequency is lower than the first resonant frequency. The first filtering element shows a high impedance towards the electronic signal with the first resonant frequency to prevent the first resonant frequency signal from entering the second resonance unit. Further, the first filtering element shows a low impedance towards the second resonant frequency signal, with the second resonant frequency signal being capable of passing through the first filtering element.

BRIEF DESCRIPTION OF THE DRAWINGS

The structure as well as preferred modes of use, further objects, and advantages of this invention will be best understood by referring to the following detailed descriptions of illustrated embodiments in conjunction with the accompanying drawings, in which:

FIG. 1 is a perspective view of a multi-frequency antenna according to an embodiment of the invention.

FIG. 2 is a perspective view of a multi-frequency antenna according to another embodiment of the invention.

FIG. 3 is a perspective view of a multi-frequency antenna according to another embodiment of the invention.

FIG. 4 is a perspective view of a multi-frequency antenna according to another embodiment of the invention.

FIG. 5 is a perspective view of a multi-frequency antenna according to another embodiment of the invention.

FIG. 6 is a perspective view of a multi-frequency antenna according to another embodiment of the invention.

FIG. 7 is a perspective view of a multi-frequency antenna according to another embodiment of the invention.

FIG. 8 is a perspective view of a multi-frequency antenna according to another embodiment of the invention.

FIG. 9 is a perspective view of a multi-frequency antenna according to another embodiment of the invention.

FIG. 10 is a perspective view of a multi-frequency antenna according to another embodiment of the invention.

FIG. 11 is a perspective view of a multi-frequency antenna according to another embodiment of the invention.

FIG. 12 is a perspective view of a multi-frequency antenna according to another embodiment of the invention.

FIG. 13 is a perspective view of a multi-frequency antenna according to another embodiment of the invention.

FIG. 14 is a perspective view of a multi-frequency antenna according to another embodiment of the invention.

DETAILED DESCRIPTION OF THE PREFERRED EMBODIMENTS

FIG. 1 is a perspective view of a multi-frequency antenna according to an embodiment of the invention. The multi-frequency antenna 10 comprises a circuit board 11, at least one substrate 13, a first resonance unit 15, a first filtering element 171, and a second resonance unit 18. The circuit board 11 comprises a clearance area 111 and at least one

signal feeding terminal 113, and the substrate 13 is disposed within the clearance area 111 of the circuit board 11, wherein the clearance area is a region on the substrate without ground plane.

One end of the first resonance unit 15 is connected to the signal feeding terminal 113, and the other end of the first resonance unit 15 is connected to the first filtering element 171. Partial or all of the first resonance unit 15 may be located on the surface of the substrate 13 or within the substrate 13. For example, portion of the first resonance unit 15 is located on the surface of the substrate 13, portion of the first resonance unit 15 is located within the clearance area 111 of the circuit board 11 to connect with the signal feeding terminal 113 and portion of the first resonance unit 15 is embedded within the substrate 13.

The second resonance unit 18 is connected to the first filtering element 171, and thus the first filtering element 171 is located between the first resonance unit 15 and the second resonance unit 18. Part or all of the second resonance unit 18 may be located on the surface of the substrate 13 or within the substrate 13.

The first resonance unit 15 is used to form the first resonant frequency f_1 of the multi-frequency antenna 10, and the first resonance unit 15, the first filtering element 171, and the second resonance unit 18 jointly form the second resonant frequency f_2 of the multi-frequency antenna 10. The second resonant frequency f_2 is lower than the first resonant frequency f_1 .

More specifically, the first filtering element 171 shows a high impedance towards the electronic signal with first resonant frequency f_1 , and the first resonant frequency signal f_1 is isolated from the second resonance unit 18 without transmitting to the second resonance unit 18. Furthermore, the first filtering element 171 shows a low impedance towards the signal with the second resonant frequency f_2 , and thus the second resonant frequency signal f_2 can pass through the first filtering element 171.

In practical application, a suitable first filtering element 171 may be selected based on the first resonant frequency f_1 and the second resonant frequency f_2 of the multi-frequency antenna 10. For example, the first filtering element 171 may comprise at least one inductor or a resonance circuit consisting of inductors and capacitors. Further, because the second resonant frequency f_2 is jointly formed by the first resonance unit 15, the first filtering element 171, and the second resonance unit 18, the frequency of the second resonant frequency f_2 will change based on the replacement of the first filtering element 171.

Further, the first resonance unit 15 and the second resonance unit 18 may comprise a plurality of conducting segments, such as conducting wires, connecting units, conducting planes, or curved conducting surfaces. More specifically, the conducting wire, the conducting plane, or the curved conducting surface is disposed on the surface of the substrate 13, within the substrate 13, or within the clearance area 111 of the circuit board 11, and the connecting unit penetrates through part or all of the substrate 13 in order to connect with the conducting wire, the conducting plane, or the curved conducting surface.

In this embodiment of the invention, the first resonance unit 15 may comprise a plurality of first conducting layers 151, such as conducting wires, and a plurality of first connecting units 153. Each first conducting layer 151 may be respectively disposed on different planes or surfaces of the substrate 13. For example, the first conducting layers 151 are disposed on the top surface and/or the bottom surface of the substrate 13. The first connecting units 153 that penetrate

through part or all of the substrate 13 are connected with first conducting layers 151 disposed on different planes or surfaces of the substrate 13. Similarly, the second resonance unit 18 may also comprise a plurality of second conducting layers 181, such as conducting wires, and a plurality of second connecting units 183. Each second conducting layer 181 may be disposed on different planes or surfaces of the substrate 13. For example, the second conducting layers 181 are disposed on the top surface and/or the bottom surface of the substrate 13. The second connecting units 183 that penetrate through part or all of the substrate 13 are connected to the second conducting layers 151 disposed on different planes or surfaces of the substrate 13.

In this embodiment of the invention, the first filtering element 171 is disposed on the surface of the substrate 13, as shown in FIG. 1. In another embodiment of the invention, the first filtering element 171 may be disposed within the clearance area 111 of the circuit board 11, and the first resonance unit 15 and the second resonance unit 18 are connected to the first filtering element 171 within the clearance area 111 by the conducting wires within the clearance area 111, as shown in FIG. 2.

FIG. 3 is a perspective view of a multi-frequency antenna according to another embodiment of the invention. The multi-frequency antenna 20 comprises a circuit board 11, at least one substrate 13, a first resonance unit 15, a first filtering element 271, a second resonance unit 18, a second filtering element 273, and a third resonance unit 29. The circuit board 11 comprises a clearance area 111 and at least one signal feeding terminal 113, and the substrate 13 is disposed within the clearance area 111 of the circuit board 11.

One end of the first resonance unit 15 is connected to the signal feeding terminal 113, and the other end of the first resonance unit 15 is connected to one end of the first filtering element 271, wherein part or all of the first resonance unit 15 is located on the surface of the substrate 13 or within the substrate 13. For example, part of the first resonance unit 15 is disposed on the surface and interior of the substrate 13, and part of the first resonance unit 15 is disposed within the clearance area 111 of the circuit board 11 in order to connect to the signal feeding terminal 113.

The second resonance unit 18 is connected to the other end of the first filtering element 271, and thus the first filtering element 171 is disposed between the first resonance unit 15 and the second resonance unit 18, wherein part or all of the second resonance unit 18 is disposed on the surface of the substrate 13 or within the substrate 13.

One end of the second filtering element 273 is connected to the second resonance unit 18, and the third resonance unit 29 is connected to the other end of the second filtering element 273. Thus, the second filtering element 273 is disposed between the second resonance unit 18 and the third resonance unit 29, and part or all of the third resonance unit 29 is disposed on the surface of or within the substrate 13. The first filtering element 271 and the second filtering element 273 may respectively comprise at least one inductor or a resonant circuit consisting of capacitors and inductors.

The first resonance unit 15 forms the first resonant frequency f_1 of the multi-frequency antenna 20, and the first resonance unit 15, the first filtering element 271, and the second resonance unit 18 jointly form the second resonant frequency f_2 of the multi-frequency antenna 20, wherein the second resonant frequency f_2 is lower than the first resonant frequency f_1 . Further, the first resonance unit 15, the first filtering element 271, the second resonance unit 18, the second filtering element 273, and the third resonance unit 29

jointly form a third resonant frequency f_3 of the multi-frequency antenna **20**, and the third resonant frequency f_3 is lower than the second resonant frequency f_2 .

More specifically, the first filtering element **271** shows a high impedance towards the signal with the first resonant frequency f_1 to isolate the first resonant frequency signal f_1 from the second resonance unit **18**. Thus, the signal with the first resonant frequency f_1 is unable to be transmitted to the second resonance unit **18**. Further, the first filtering element **271** shows a low impedance towards the signals with the second resonant frequency f_2 and the third resonant frequency f_3 . Thus, the second resonant frequency signal f_2 and the third resonant frequency signal f_3 can pass through the first filtering element **271**.

The second filtering element **273** shows a high impedance towards signal with the second resonant frequency f_2 to isolate the second resonant frequency signal f_2 from the third resonance unit **29**. Thus, the second resonant frequency signal f_2 is unable to be transmitted to the third resonance unit **29**. Furthermore, the second filtering element **273** shows a low impedance towards the signal with the third resonant frequency f_3 , and thus the third resonant frequency signal f_3 can pass through the second filtering element **273**.

In one embodiment of the invention, the third resonance unit **29** comprises a plurality of conducting segments, such as conducting wires, connecting units, conducting planes, or curved conducting surfaces. In this embodiment of the invention, the third resonance unit **29** comprises a plurality of third conducting layers **291**, such as conducting wires, and a plurality of third connecting units **293**, wherein each third conducting layer **291** is disposed on different planes or surfaces of the substrate **13**. For example, each third conducting layer **291** is disposed on the top or bottom surface of the substrate **13**. The third connecting unit **293** passes through part or all of the substrate **13** in order to connect to the third conducting layers **291** disposed on different planes or surfaces of the substrate **13**.

In this embodiment of the invention, the first filtering element **271** and the second filtering element **273** are disposed on the surface of the substrate **13**, as shown in FIG. 3. In another embodiment of the invention, the first filtering element **271** and the second filtering element **273** may be disposed within the clearance area **111** of the circuit board **11**, and the first resonance unit **15** and the second resonance unit **18** are connected to the first filtering element **271** within the clearance area **111** via the conducting wires within the clearance area **111**. The second resonance unit **18** and the third resonance unit **29** are connected to the second filtering element **273** within the clearance area **111** via the conducting wires within the clearance area **111**, as shown in FIG. 4. In another embodiment of the invention, the first filtering element **271** may be disposed on the surface of the substrate **13**, and the second filtering element **273** may be disposed within the clearance area **111**. In another embodiment of the invention, the second filtering element **273** may be disposed on the surface of the substrate **13**, and the first filtering element **271** may be disposed within the clearance area **111**.

FIG. 5 is a perspective view of a multi-frequency antenna according to another embodiment of the invention. The multi-frequency antenna **30** comprises a circuit board **11**, at least one substrate **13**, a first resonance unit **35**, a first filtering element **371**, and a second resonance unit **38**. The circuit board **11** comprises a clearance area **111** and at least one signal feeding terminal **113**, and the substrate **13** is disposed within the clearance area **111** of the circuit board **11**.

The first resonance unit **35** is connected to the signal feeding terminal **113**, and part or all of the first resonance unit **35** is disposed on the surface of or within the substrate **13**. For example, part of the first resonance unit **35** is disposed on the surface of the substrate **13** or within the substrate **13**, and part of the first resonance unit **35** is disposed within the clearance area **111** of the circuit board **11** in order to connect to the signal feeding terminal **113**. The second resonance unit **38** is connected to the first resonance unit **35** via the first filtering element **371**, and thus the first filtering element **371** is located between the first resonance unit **35** and the second resonance unit **38**, wherein part or all of the second resonance unit **38** is disposed on the surface of the substrate **13** or within the substrate **13**.

The first resonance unit **35** forms the first resonant frequency f_1 of the multi-frequency antenna **30**, and the first resonance unit **35**, the first filtering element **371**, and the second resonance unit **38** jointly form the second resonant frequency f_2 of the multi-frequency antenna **30**, wherein the frequency of the second resonant frequency f_2 is lower than the first resonant frequency f_1 . Further, the first filtering element **371** shows a high impedance towards the signal with the first resonant frequency f_1 to isolate the first resonant frequency signal f_1 from the second resonance unit **38**. The first filtering element **371** shows a low impedance towards the signal with the second resonant frequency f_2 , thus the second resonant frequency signal f_2 can pass through the first filtering element **371**.

In one embodiment of the invention, the first resonance unit **35** comprises a first conducting plane **351**, and the second resonance unit **38** comprises a second conducting plane **381** and a rounded conducting plane **382** with curve boundary. For example, the first conducting plane **351** and the second conducting plane **381** may be a square, and the rounded conducting plane **382** may comprise region with curve boundary. The second conducting plane **381** is connected to the rounded conducting plane **382**.

In this embodiment of the invention, the first filtering element **371** is disposed on the surface of the substrate **13**, and is connected to the first resonance unit **35** and the second resonance unit **38**. Thus, the first filtering element **371** is located between the first resonance unit **35** and the second resonance unit **38**, as shown in FIG. 5.

In another embodiment of the invention, the first filtering element **371** is disposed within the clearance area **111** of the circuit board **11**, and the first resonance unit **35** and the second resonance unit **38** are connected to the first filtering element **371** within the clearance area **111** via the conducting wires within the clearance area **111**, as shown in FIG. 6.

FIG. 7 is a perspective view of a multi-frequency antenna according to another embodiment of the invention. The multi-frequency antenna **40** comprises a circuit board **11**, at least one substrate **13**, a first resonance unit **45**, a first filtering element **471**, and a second resonance unit **48**. The circuit board **11** comprises a clearance area **111** and at least one signal feeding terminal **113**, and the substrate **13** is disposed within the clearance area **111** of the circuit board **11**.

The first resonance unit **45** is connected to the signal feeding terminal **113**, and part or all of the first resonance unit **45** is located on the surface of the substrate **13** or within the substrate **13**. For example, part of the first resonance unit **45** is disposed on the top surface of the substrate **13**, and part of the first resonance unit **45** is extended within the clearance area **111** of the circuit board **11** to connect to the signal feeding terminal **113**. The first filtering element **471** is disposed on the surface of the substrate **13**, and the second

resonance unit **48** is connected to the first resonance unit **45** via the first filtering element **471**. Part or all of the second resonance unit **48** is disposed on the surface of the substrate **13**, such as the top surface, or within the substrate **13**.

In one embodiment of the invention, the multi-frequency antenna **40** comprises at least one extended unit **46** disposed on the surface of the substrate **13** or within the substrate **13**. One end of the extended unit **46** is connected to the first resonance unit **45**, such as the extended unit **46** disposed on the top surface of the substrate **13**, as shown in FIG. 7. In another embodiment, the extended unit **46** may be extended to the clearance area **111** of the circuit board **11**. For example, one end of the extended unit **46** is connected to the first resonance unit **45**. Part of the extended unit **46** is disposed on the surface or the top surface of the substrate **13**, and part of the extended unit **46** is extended to the clearance area **111** via the side surface of the substrate **13**, as shown in FIG. 8.

In another embodiment of the invention, the extended unit **46** may be connected to the second resonance unit **48**, wherein the extended unit **46** is disposed on the surface of the substrate **13** or within the substrate **13**, or is extended to the clearance area **111** of the circuit board **11**. For example, one end of the extended unit **46** is connected to the second resonance unit **48**. Part of the extended unit **46** is disposed on the surface of the substrate **13** or within the substrate **13**, and part of the extended unit **46** is extended to the clearance area **111** via the side surface of the substrate **13**, as shown in FIG. 9.

FIG. 10 is a perspective view of a multi-frequency antenna according to another embodiment of the invention. The multi-frequency antenna **50** comprises a circuit board **11**, at least one substrate **13**, a first resonance unit **55**, a first filtering element **571**, a second resonance unit **58**, and a coupling unit **56**. The circuit board **11** comprises a clearance area **111** and at least one signal feeding terminal **113**, and the substrate **13** is disposed within the clearance area **111** of the circuit board **11**.

The first resonance unit **55** is connected to the signal feeding terminal **113**, and part or all of the first resonance unit **55** is located on the surface of the substrate **13** or within the substrate **13**. For example, part of the first resonance unit **55** is disposed on the top surface or the side surface of the substrate **13**, and part of the first resonance unit **55** is disposed within the clearance area **111** of the circuit board **11** to connect to the signal feeding terminal **113**. The first filtering element **571** is disposed on the surface of the substrate **13**, and the second resonance unit **58** is connected to the first resonance unit **55** via the first filtering element **571**. Part or all of the second resonance unit **58** is disposed on the surface of the substrate **13** or within the substrate **13**, such as the second resonance unit **58** being disposed on the top surface of the substrate **13**.

In one embodiment of the invention, the coupling unit **56** of the multi-frequency antenna **50** is disposed on the surface of the substrate **13** or within the substrate **13**. A portion of the first resonance unit **55** is adjacent to partial portion of the coupling unit **56** to form a gap **52** therebetween. For example, part of the coupling unit **56** is disposed on the top surface and/or side surface of the substrate **13**, and part of the coupling unit **56** is disposed within the clearance area **111**. In another embodiment, one end of the coupling unit **56** is connected to the ground layer **115** of the circuit board **11**. Further, the shape of the coupling unit **56** may be similar to the shapes of the first resonance unit **55** and the second resonance unit **58**. However, this is one embodiment of the invention and is not a limitation of the invention. In another

embodiment, the coupling unit **56** may not be connected to the ground layer **115**, and the shape of the coupling unit **56** may not be similar to the shape of the first and second resonance unit **55/58**.

FIG. 11 is a perspective view of a multi-frequency antenna according to another embodiment of the invention. The multi-frequency antenna **60** comprises a circuit board **11**, at least one substrate **13**, a first resonance unit **65**, a first filtering element **671**, and a second resonance unit **68**. The circuit board **11** comprises a clearance area **111** and at least one signal feeding terminal **113**, and the substrate **13** is disposed within the clearance area **111** of the circuit board **11**.

In one embodiment of the invention, the first resonance unit **65** is connected to the signal feeding terminal **113**, and part or all of the first resonance unit **65** is located on the surface of the substrate **13** or within the substrate **13**. For example, part of the first resonance unit **65** is disposed on the bottom surface of the substrate **13**, and part of the first resonance unit **65** is extended to the clearance area **111** of the circuit board **11** to connect to the signal feeding terminal **113**. The first filtering element **671** is disposed within the clearance area **111** of the circuit board **11**, and the second resonance unit **68** is connected to the first resonance unit **65** via the first filtering element **671**. Part or all of the second resonance unit **68** is disposed on the surface of the substrate **13** or within the substrate **13**, such as the second resonance unit **68** being disposed on the bottom surface of the substrate **13**.

In one embodiment of the invention, the multi-frequency antenna **60** further comprises at least one extended unit **66**, and one end of the extended unit **66** is connected to the first resonance unit **65**. Part of the extended unit **66** is disposed on the surface of the substrate **13**, and part of the extended unit **66** is extended to the clearance area **111**. For example, part of the extended unit **66** is disposed on the bottom surface of the substrate **13**, and part of the extended unit **66** is extended to the clearance area **111**, as shown in FIG. 11. In another embodiment, instead of connecting to the first resonance unit **65**, the extended unit **66** may be connected to the second resonance unit **68**.

In another embodiment of the invention, the circuit board **11** further comprises a ground layer **115**, and the extended unit **66** shown in FIG. 11 may be connected to the ground layer **115** via a ground wire **661**. The ground wire **661** is able to connect to the first resonance unit **65** and the ground layer **115**, as shown in FIG. 12. In another embodiment, instead of connecting to the first resonance unit **65**, the ground wire **661** may be connected to the second resonance unit **68** and the ground layer **115**.

FIG. 13 is a perspective view of a multi-frequency antenna according to another embodiment of the invention. The multi-frequency antenna **70** comprises a circuit board **11**, at least one substrate **13**, a first resonance unit **75**, a first filtering element **771**, and a second resonance unit **78**. The circuit board **11** comprises a clearance area **111** and at least one signal feeding terminal **113**, and the substrate **13** is disposed within the clearance area **111** of the circuit board **11**.

One end of the first resonance unit **75** is connected to the signal feeding terminal **113**, and the other end of the first resonance unit **75** is connected to the first filtering element **771**. The second resonance unit **78** is connected to the first resonance unit **75** via the first filtering element **771**, thus the first filtering element **771** is located between the first resonance unit **75** and the second resonance unit **78**.

In this embodiment of the invention, the first resonance unit 75 comprises a plurality of first conducting layers 751 and at least one first connecting unit 753. Each first conducting layer 751 may be disposed on different planes or surfaces of the substrate 13, and the first connecting unit 753 penetrates through part or all of the substrate 13 in order to connect with the first conducting layers 751 disposed on different planes or surfaces of the substrate 13. For example, part of the first conducting layer 751 is disposed on the bottom surface of the substrate 13, and part of the first conducting layer 751 is disposed on the top surface of the substrate 13. Further, the first conducting layers 751 disposed on the top surface and the bottom surface of the substrate 13 are connected to each other via the first connecting unit 753.

Furthermore, the second resonance unit 78 comprises a plurality of second conducting layer 781 and at least one second connecting unit 783. Each second conducting layer 781 is disposed on different planes or surfaces of the substrate 13 respectively, and the second connecting unit 783 penetrates through part or all of the substrate 13 and is connected to the second conducting layers 781 disposed on different planes or surfaces of the substrate 13. For example, part of the second conducting layer 781 is disposed on the bottom surface of the substrate 13, and part of the second conducting layer 781 is disposed within the substrate 13. Further, the second conducting layers 781 disposed on the bottom surface of the substrate 13 and within the substrate 13 are connected to each other via the second connecting unit 783.

FIG. 14 is a perspective view of a multi-frequency antenna according to another embodiment of the invention. The multi-frequency antenna 80 comprises a circuit board 11, at least one substrate 13, a first resonance unit 85, a first filtering element 871, and a second resonance unit 88. The circuit board 11 comprises a clearance area 111 and at least one signal feeding terminal 113, and the substrate 13 is disposed within the clearance area 111 of the circuit board 11. The first filtering element 871 can be disposed on the surface of substrate 13 or in the clearance area 111 of the circuit board 11.

In this embodiment of the invention, the first resonance unit 85 comprises a plurality of first conducting wires 851, and part or all of the first resonance unit 85 is disposed on the surface of the substrate 13 or within the substrate 13. For example, part of the first resonance unit 85 is disposed on the top surface of the substrate 13, and part of the first resonance unit 85 is extended to the clearance area 111 via the side surface of the substrate 13. One end of each first conducting wire 851 can be connected to the signal feeding terminal 113, and the other end of each first conducting wire 851 can be connected to the first filtering element 871. Further, the second resonance unit 88 comprises a plurality of second conducting wires 881. One end of each second conducting wire 881 can be connected to the first filtering element 871, and the other end of each second conducting wire 881 can or cannot be connected to each other. Furthermore, part or all of the second resonance unit 88 is disposed on the surface of the substrate 13 or within the substrate 13. For example, part of the second resonance unit 88 is disposed on the top surface of the substrate 13, and part of the second resonance unit 88 is extended to the clearance area 111 via the side surface of the substrate 13.

The first resonance units 15/35/45/55/65/75/85, the second resonance units 18/38/48/58/68/78/88, and/or the third resonance unit 29 described in the invention can be disposed

on any surface of the substrate 13, such as on the top surface, the bottom surface, or the side surface of the substrate, or within the substrate 13.

The above disclosures are only the preferred embodiments of the present invention, and are not to be used to limit the scope of the present invention. All equivalent variations and modifications on the basis of shapes, structures, features, and spirits described in the claims of the present invention should be included in the claims of the present invention.

What is claimed is:

1. A multi-frequency antenna comprising:
a circuit board, comprising a ground layer, a clearance area and at least one signal feeding terminal;
at least one substrate disposed within said clearance area;
a first resonance unit connected to said signal feeding terminal, wherein part or all of said first resonance unit is disposed on a surface of said substrate or within said substrate;
a first filtering element connected to said first resonance unit; and
a second resonance unit connected to said first filtering element, and thus said first filtering element is disposed between said first resonance unit and said second resonance unit, wherein part or all of said second resonance unit is disposed on said surface of said substrate or within said substrate, wherein said first resonance unit forms a first resonant frequency of said multi-frequency antenna, and said first resonance unit, said first filtering element and said second resonance unit jointly form a second resonant frequency of said multi-frequency antenna, wherein said first filtering element shows a high impedance towards a signal with said first resonant frequency to isolate said first resonant frequency signal from said second resonance unit, wherein said first filtering element shows a low impedance towards a signal with said second resonant frequency, and said second resonant frequency signal is capable of passing through said first filtering element, wherein said second resonant frequency is lower than said first resonant frequency, and said second resonant frequency is independent of said first resonant frequency, wherein there is no any switch between said first resonance unit, said first filtering element, said second resonance unit and said ground layer.

2. The multi-frequency antenna of claim 1, wherein said first resonance unit and said second resonance unit comprise a plurality of conducting segments, and said conducting segment comprises a conducting wire, a connecting unit, a conducting plane, or a curved conducting surface, wherein said conducting wire, said conducting plane, or said curved conducting surface is disposed on said surface of said substrate or within said substrate or within said clearance area, and the connecting unit penetrates through part or all of the substrate to connect with said conducting wire, said conducting plane, or said curved conducting surface.

3. The multi-frequency antenna of claim 1, wherein said first filtering element is disposed on the surface of said substrate or within said substrate or within said clearance area.

4. The multi-frequency antenna of claim 1, wherein said first resonance unit comprises a plurality of first conducting layers disposed on different planes of said substrate, and at least one first connecting unit connecting said first conducting layers, wherein said second resonance unit comprises a plurality of second conducting layers disposed on different

11

planes of said substrate, and at least one second connecting unit connecting said second conducting layers.

5. The multi-frequency antenna of claim 1, further comprising at least one extended unit disposed within said clearance area and electrically connected to said first resonance unit or said second resonance unit. 5

6. The multi-frequency antenna of claim 1, further comprising at least one extended unit disposed on the surface of said substrate or within said substrate and electrically connected to said first resonance unit or said second resonance 10 unit. 10

7. The multi-frequency antenna of claim 1, further comprising at least one ground wire connecting said ground layer with said first resonance unit or said second resonance 15 unit.

8. The multi-frequency antenna of claim 7, wherein said first filtering element comprises at least one inductor or a resonant circuit inductors and capacitors. 15

9. The multi-frequency antenna of claim 1, further comprising a coupling unit disposed on said surface of said substrate or within said substrate, wherein a gap is formed between part or all of said coupling unit and part or all of said first resonance unit or said second resonance unit to form a coupling effect. 20

10. The multi-frequency antenna of claim 1, wherein said second resonance unit is not connected to said ground layer. 25

11. A multi-frequency antenna comprising:
a circuit board, comprising a clearance area and at least one signal feeding terminal;
at least one substrate disposed within said clearance area; 30
a first resonance unit connected to said signal feeding terminal, wherein part or all of said first resonance unit is disposed on a surface of said substrate or within said substrate;
a first filtering element connected to said first resonance 35 unit;
a second resonance unit connected to said first filtering element, and thus said first filtering element is disposed between said first resonance unit and said second resonance unit, wherein part or all of said second resonance unit is disposed on said surface of said substrate or within said substrate, wherein said first 40

12

resonance unit forms a first resonant frequency of said multi-frequency antenna, and said first resonance unit, said first filtering element and said second resonance unit jointly form a second resonant frequency of said multi-frequency antenna, wherein said first filtering element shows a high impedance towards a signal with said first resonant frequency to isolate said first resonant frequency signal from said second resonance unit, wherein said first filtering element shows a low impedance towards a signal with said second resonant frequency, and said second resonant frequency signal is capable of passing through said first filtering element, wherein said second resonant frequency is lower than said first resonant frequency;

a second filtering element connected to said second resonance unit; and

a third resonance unit connected to said second filtering element, and thus said second filtering element disposed between said second resonance unit and said third resonance unit, wherein part or all of said third resonance unit is disposed on said surface of said substrate or within said substrate, wherein said first resonance unit, said first filtering element, said second resonance unit, said second filtering element, and said third resonance unit jointly form a third resonant frequency of said multi-frequency antenna, wherein said second filtering element shows a high impedance towards the signal with said second resonant frequency to isolate said second resonant frequency signal from said third resonance unit, wherein said second filtering element shows a low impedance towards signal with said third resonant frequency, and said third resonant frequency signal is capable of passing through said second filtering element, wherein said third resonant frequency is lower than said second resonant frequency.

12. The multi-frequency antenna of claim 11, wherein said second filtering element is disposed on said surface of said substrate or within said substrate or within said clearance area.
